(57) **CLAIM**

The ornamental design for a tool belt and pouches, as shown and described.

DESCRIPTION

FIG. 1 is a front perspective view of the tool belt and pouches showing our new design.

FIG. 2 is a top view thereof.

FIG. 3 is a front elevational view thereof.

FIG. 4 is a left side elevational view thereof.

FIG. 5 is a right side elevational view thereof.

FIG. 6 is a rear elevational view thereof; and,
FIG. 7 is a bottom view thereof.

The tool belt and pouches are made from a combination of cloth and leather.
